(57) **CLAIM**

The ornamental design of a lighting control device, as shown and described.

DESCRIPTION

FIG. 1 illustrates a side perspective view of a lighting control device showing our new design.

FIG. 2 illustrates a front view of the lighting control device thereof.

FIG. 3 illustrates a rear view of the lighting control device thereof.

FIG. 4 illustrates a left side view of the lighting control device thereof.

FIG. 5 illustrates a right side view of the lighting control device thereof.

FIG. 6 illustrates a top view of the lighting control device thereof.

FIG. 7 illustrates a bottom view of the lighting control device thereof.

FIG. 8 illustrates a side perspective view of a lighting control device showing an alternate position of the slots shown in broken lines.

FIG. 9 illustrates a front view of the lighting control device thereof.

FIG. 10 illustrates a rear view of the lighting control device thereof.

FIG. 11 illustrates a left side view of the lighting control device thereof.

FIG. 12 illustrates a right side view of the lighting control device thereof.

FIG. 13 illustrates a top view of the lighting control device thereof; and,

FIG. 14 illustrates a bottom view of the lighting control device thereof.

The broken lines in the figures show portions of the lighting control device that form no part of the claimed design.
